UNITED STATES PATENT OFFICE.

ARTHUR J. BRIGGS, OF SYRACUSE, NEW YORK, ASSIGNOR TO REMINGTON TYPE-WRITER COMPANY, OF ILLION, NEW YORK, A CORPORATION OF NEW YORK.

TYPE-WRITING MACHINE.

1,239,872.

Specification of Letters Patent. Patented Sept. 11, 1917.

Application filed August 22, 1916. Serial No. 117,260.

To all whom it may concern:

Be it known that I, ARTHUR J. BRIGGS, citizen of the United States, and resident of Syracuse, in the county of Onondaga and State of New York, have invented certain new and useful Improvements in Type-Writing Machines, of which the following is a specification.

My invention relates to typewriting machines and more particularly to the margin stop mechanism of such machines.

My invention has for its principal object to provide margin stops of improved and simple construction.

My invention consists of certain features of construction and combinations and arrangements of parts, all of which will be fully set forth herein and particularly pointed out in the claims.

In the accompanying drawings,

Figure 1 is a rear elevation, partly in section, of so much of the carriage and stationary framework of a typewriting machine as is necessary to illustrate the invention.

Fig. 2 is a left-hand end elevation of the upper rear part of the typewriting machine.

Fig. 3 is a fragmentary plan view of the adjustable margin stop and its coöperating parts, some parts being broken away.

Fig. 4 is a perspective view of the adjustable stop.

The main frame of the machine can be of any suitable construction as far as the present invention is concerned, top plates 1 and carriage rails 2 and 3 being illustrated in the drawing. The rail 2, in the form here shown, consists of a bar or casting lying across the back part of the typewriting machine and having a ball bearing groove in its forward edge as shown in Fig. 2. The rail 3 consists of a plate of sheet metal suitably secured to the rear edge of the casting 2 by screws threaded into holes 4, said plate at its upper part being bent first forward at an inclination of 45° and thence backward to form a V-groove facing the rear. The carriage comprises a rail part 5 consisting of a bar of sheet metal having its middle portion horizontal as shown in Fig. 2 and bent down along its forward part at an inclination of 45° and thence rearward to form a grooved rail 6 facing the groove in

the rail 2; and said bar 5 is bent down at its rear part and thence forward forming a rail 7 facing the rail 3. Anti-friction balls 8 complete the ball bearing support of the carriage. Said carriage can be constructed in any suitable way. As here shown it has brackets 10 at the ends thereof and in which is journaled the axle of a platen 11 having finger wheels 12 and a line spacing wheel 13. Coöperating with said wheel 12 is the dog 14 of a line space mechanism, said dog being pivoted at 15 on an arm 16 at the rear end of a rock shaft 17 journaled in one of the brackets 10, and said shaft at its forward end carrying a line space handle 18. The degree of movement of the line space mechanism is regulated by setting a handle 20, the regulation being effected by means not necessary here to be shown or described.

Fig. 2 shows parts 21 of a carriage release mechanism also not necessary to be further described. A spring drum 22 and cord 23 are shown for propelling the carriage toward the left.

My adjustable margin stop piece, as shown in the present instance, is mounted on top of the rail casting 2, the stop itself, Figs. 1 and 4, consisting of a lug 24 projecting upward from one end of a horizontal bar 25 having a roughened finger piece 26 at its opposite end. The bar 25 is wider than the lug 24 and thumb piece 26 and on one side it has a locking tooth 27 for retaining it in adjusted position. Beneath the stop lug 24 the bar 25 has a rounded part 28 and a flat spring 30 is riveted to the bar 25 at 31, said spring pressing against the upper surface of the casting 2. Said flat part of the casting is depressed below the upper part of the front carriage rail and at its forward part said rail has an undercut 32 in which the forward edge of the bar 25 lies. In order to complete a T-groove for said bar to lie in, a bar 33 is secured to the upper part of the casting 2 by means of screws 34, and said bar is also undercut and the projecting flange is formed with a series of rack teeth 35 with interdental notches into any one of which, according to adjustment, the locking tooth 27 can be pressed by the spring 30. The whole construction is such that normally said locking tooth occupies one of the

notches in the bar 33 but by pressing down on the finger piece 26 and thus bending the spring 30, said locking tooth can be moved out of engagement with the said bar and 5 the whole device can then be slid in a right or left-hand direction to any desired position. It will, of course, be understood that the teeth 35 are spaced letter space distances apart and preferably graduations 36 are 10 formed or imprinted on the upper surface of the bar 33 to facilitate adjustment of the stop, and these graduations are here shown as designated with numerals corresponding to those on the scale plate of the carriage.

15 The stop for coöperation with the stop 24 consists of a lug 37 projecting downward from the under surface of the rail bar 5 at the left-hand end of said bar.

It will be perceived from Fig. 1 that the 20 stop 24 is located beneath the carriage and that in most positions of the carriage the finger piece 26 is also covered up by the carriage but when the carriage is drawn to the operator's right it will be arrested by 25 the stop 37 striking the stop 24 and in this position the finger piece 26 is accessible at the left-hand end of the carriage. The stop can then be readily adjusted by pressing down on the said finger piece to withdraw 30 the locking tooth 27 from the rack teeth 35, and then moving the stop piece and the carriage together to the letter space position at which it is desired to have the carriage arrested, and then releasing the finger piece 35. 26. The spring 30 will then move the locking tooth 27 into engagement with the teeth 35 and retain the adjustable stop in its set position.

It will be noted that the release key 21 40 and the finger piece 26 are near each other when the carriage is in its right-hand position so that the carriage and finger piece can be moved back and forth together conveniently.

45 It will be noted that this margin stop mechanism is of extremely simple construction; that it is readily adjustable; and that it is strong and effective.

Various changes can be made in the 50 details of construction and arrangement without departing from my invention.

What I claim as new and desire to secure by Letters Patent, is:—

1. In a typewriting machine and in margin stop mechanism, the combination with a carriage comprising two roller-bearing rails and a coöperating track-way; of a spring-pressed margin stop piece mounted in said coöperating track-way, said track-way having 55 means for guiding said stop piece, and said stop piece comprising a bar with a stop lug on one end thereof, and a finger piece on the other end, said finger piece when the carriage is at one end of its travel 60 projecting beyond the end of the carriage 65

and being under the carriage at other times; means for holding said stop piece in adjusted position comprising a rack in the track-way and a tooth on the stop piece; and a coöperating stop on the carriage. 70

2. In a typewriting machine and in margin stop mechanism, the combination with a carriage; of a bar having an undercut therein; a second bar mounted on the first mentioned bar and having a projecting 75 toothed flange to define a second undercut facing the undercut in the first-mentioned bar; a margin stop piece mounted in the undercut groove defined by the two said bars and having a locking tooth to engage 80 the teeth of said flange, and said margin stop piece having a stop lug thereon, and a spring for pressing said locking tooth into said flange teeth; and a coöperating stop. 85

3. In a typewriting machine and in margin stop mechanism, the combination with a carriage; of a bar having an undercut groove therein with rack teeth along said groove; a margin stop piece comprising a bar having a stop lug at one end thereof and 90 a finger piece at the other end thereof and a locking tooth adjacent said finger piece; a spring acting on said bar and normally holding said locking tooth in engagement 95 with said rack teeth; and a coöperating stop. 100

4. In a typewriting machine, the combination with a carriage, of a bar having an undercut groove therein; a second bar mounted on the first mentioned bar and having an undercut to form a flange which flange is formed with rack teeth; a margin stop piece comprising a bar lying in said undercut groove; a stop lug at one end of said bar and projecting through said groove, a finger 105 piece and a locking tooth at the other end of said bar, and a spring under said bar to hold said locking tooth in engagement with said rack; and a coöperating stop. 110

5. In a typewriting machine, the combination with a carriage, of a trackway on which said carriage travels, said trackway having an undercut groove, a flange, a toothed bar secured to said trackway so as to form a second undercut facing the undercut in the 115 trackway, a margin stop piece mounted in the undercut groove and comprising a bar having a stop lug on the inner end thereof, and a finger piece on the outer end thereof with a locking tooth to engage said rack 120 teeth, the construction being such that when the carriage is at one end of its travel said finger piece projects beyond the end of the carriage; and a coöperating stop. 125

6. In a typewriting machine and in margin stop mechanism, the combination of a carriage; a track-way arranged therebelow; a rack fixedly attached to said track-way; a spring-pressed margin stop piece adjustably mounted in said track-way and com- 130

prising a bar provided with a locking tooth to engage said rack and also comprising a finger piece and a stop lug; and a cooperating stop for the latter mounted on the under side of the carriage and over said track-way.

Signed at Syracuse, in the county of

Onondaga and State of New York this 24th day of August A. D. 1916.

ARTHUR J. BRIGGS.
